DESIGN FOR A TRAILER

Frank D. Hanson, Independence, Mo., and David D. Arehart and Ralph T. Dittmer, Flint, Mich., assignors to Palace Corporation, Flint, Mich., a corporation of Michigan

Application November 25, 1947, Serial No. 142,803

Term of patent 14 years

(Cl. D14—3)

To all whom it may concern:

Be it known that we, Frank D. Hanson, David D. Arehart, and Ralph T. Dittmer, citizens of the United States, residing, respectively, at Independence, in the county of Jackson and State of Missouri; at Flint, in the county of Genesee and State of Michigan; and at Flint, in the county of Genesee and State of Michigan, have invented a new, original, and ornamental Design for a Trailer, of which the following is a specification, reference being made to the accompanying drawings, forming a part thereof.

In the drawings—

Fig. 1 is a side elevational view of a trailer embodying the design;

Fig. 2 is a side elevation of the trailer shown in Fig. 1 as viewed from the opposite side;

Fig. 3 is a rear elevational view of the trailer embodying the design; and

Fig. 4 is a front elevation of a trailer embodying the design.

We claim:

The ornamental design for a trailer, substantially as shown.

FRANK D. HANSON.
DAVID D. AREHART.
RALPH T. DITTMER.
